UNITED STATES PATENT OFFICE

HELEN LEE E. DOHERTY, OF NEW YORK, N. Y.

DESIGN FOR AN AUTOMOBILE BODY

Application filed December 15, 1930. Serial No. 38,000. Term of patent 3½ years.

To all whom it may concern:

Be it known that I, HELEN LEE E. DOHERTY, a citizen of the United States, residing at New York, in the county of New York and State of New York, have invented a new, original, and ornamental Design for an Automobile Body, of which the following is a specification, reference being had to the accompanying drawings, forming part thereof.

Figure 1 is a side elevation of an automobile body with front and rear end portions broken away, showing my new design;

Figure 2 is a rear end elevation thereof with parts broken away.

The parts of the body not illustrated in the views are of conventional contour.

The opposite side of Fig. 1 is ornamented in the manner disclosed in this view.

I claim:

The ornamental design for an automobile body, as shown and described.

HELEN LEE E. DOHERTY.
